UNITED STATES PATENT OFFICE.

WILLIAM F. KOELLING, OF BERWYN, ILLINOIS.

COMBINED PARTING BEAD AND WEATHER STRIP.

Application filed October 25, 1926. Serial No. 143,880.

My invention relates to parting beads and weather strips such as are adapted to be applied to standard window frames and sashes of all kinds in order to provide a resilient seal for preventing the rattling of the sashes in the frame and excluding the cold air from the interior of the building.

One of the objects of my invention is the provision of a combined parting bead and weather strip capable of accomplishing the foregoing results, and which may be substituted for the ordinary wooden parting bead provided in the standard window frames.

Another object of my invention is the provision of such a combined parting bead and weather strip which is capable of being substituted for the ordinary parting bead in window frames without the removal of the sashes, or either of them, from the window frame.

Another object of my invention is the provision of a combined parting bead and weather strip consisting of a plurality of lengths identical in structure, which are adapted to be used in reversed position to effect resilient contact with both sashes.

Another object of my invention is the provision of such a combined parting bead and weather strip which may be cheaply manufactured, easily applied, has a minimum of parts, and which is durable and effective in providing a permanent non-rattling, air excluding seal with window sashes.

Another object of my invention is the provision of a novel combined parting bead and weather strip consisting of a plurality of lengths, having means to effect an air seal between the separate lengths of said parting bead.

Another object of my invention is the provision of a novel method of assembly in providing standard window frames with resilient weather strips.

Other objects and advantages of my invention will appear more fully from the following description and the accompanying drawings, in which similar characters of reference indicate similar parts throughout the several views.

Referring to the drawings, Figure 1 is an elevational view of a window frame, showing the application of my invention.

Figure 2 is a view in perspective of a portion of my combined parting bead and weather strip.

Figure 3 is a view in elevation taken from the left in Figure 1, showing the juncture between two lengths of my parting beads.

Figure 4 is a plan view in cross section, taken along the lines of 4—4 in Figure 1.

Figure 5 is an enlarged detail view of the bead and weather strip shown in Figure 4.

Referring to Figure 1, 10 indicates a window frame which may be any standard window frame. Such window frames usually comprise side frame members 11, which are grooved as at 12 to receive a standard wooden parting bead (not shown), and which parting bead may, according to my invention, be removed and my parting bead 13 substituted without the removal of the sashes, as hereinafter described.

The usual window and frame assembly comprises a plurality of sashes, including an upper sash 14 and a lower sash 15, but my invention may be used with any number of sashes. The upper sash 14 is usually provided at its lower end with an inwardly extending shoulder 16, which is adapted to contact with the upper outside edge of the lower sash 15, and provide a complete closure between said sashes. In order to permit the use of a parting bead in the groove 12, the shoulder 16 of the upper sash is rabbeted as at 17, and in order to provide exterior and interior sliding guides for said sashes, the frame member 11 is provided with an exterior moulding strip 18 and an interior moulding strip 19, so that the upper sash may be slid vertically between the shoulders 16 provided on the frame member 11 by the exterior moulding strip 18 and the central parting bead, and the lower sash may be slid vertically between the shoulders provided on the frame member 11 by the interior moulding strip 19 and the central parting bead. The opposite frame member, together with its parting bead and exterior and interior moulding strips, is identical in form, and, therefore, further description as to these parts appears unnecessary.

In order to remove the sashes from the window frame or to apply resilient weather strips it has been necessary to remove one or other of the moulding strips 18 or 19, thereafter removing one of the sashes and then applying the weather strip to the moulding or to the parting beads. It is particularly difficult to remove the usual parting bead without cutting or destroying the same unless

the upper sash 14 is first removed, because the shoulder 16, which is rabbeted to receive the parting bead, effectively prevents the parting bead from being removed from the 5 groove 12 without first removing the sash 14. In providing the windows with weather strips the same difficulty is encountered in placing weather strips or parting beads in the groove 12, where the said strips or beads 10 extend the full length of the window frame, and the bead must first be placed in the groove 12, after which the sash 14 is replaced and the moulding strip 18 replaced.

Another method of removing the parting bead to provide the same with a weather strip consists in removing the interior moulding strip 19 on one side of the window, removing the lower sash 15, sliding the upper sash 14 down to the bottom of the 20 window frame, at which point the shoulder 16 presents less difficulty for removing the parting bead from the groove 12. But it will be observed that by both of these 25 methods it is necessary to remove the exterior or interior moulding strips and one of the sashes.

In providing a window frame with my combined parting bead and weather strip, the existing wooden parting bead may be 30 removed by any convenient method, as by sawing part way through the same at any central point with the window open, thereafter prying or otherwise removing the said parting bead, and it will be noted that it is 35 immaterial whether this parting bead is destroyed or preserved, as my invention contemplates the substitution of a new parting bead to the sash from which it is removed, said new parting bead being provided with 40 weather strips attached thereto.

Referring to Figure 2, I will now describe the structure of my combined parting bead and weather strip. The parting bead consists of a wooden strip 20, which is here illustrated as substantially T shape in cross section. The strip 20 has a rear rectangular portion 21, which is of a size adapted to be received and to fit substantially within the groove 12 from which the standard parting bead is removed. As the rectangular portion 21 is covered in part on its rear side 22 and on its adjacent side 23 by the rear flange 24 and the side flange 25 of the weather strip which is indicated in its entirety at 26, the 50 rectangular portion 21 must necessarily be made small enough to be received in the groove 12 after the flanges 24 and 25 have been applied to said rectangular portion.

The wooden strip 20 is reduced in section 60 at its forward portion 27, which comprises all that portion of the wooden strip which will be exterior to the groove 12 when in assembled relation. This may be done by planing down the forward sides of the 65 wooden strip 20 as at 28 and 29.

The weather strip 26, which may be constructed of any resilient non-rusting metal, preferably phosphor bronze, consists of a strip of sheet metal having a flat portion 24 and another flat portion 25 at right angles 70 thereto, which are adapted to fit against the back and side of the wooden strip 20. When in assembled relation the portions 24 and 25 are concealed from view, being clamped within the groove 12. Extending from the flange 25, at a point located approximately 75 at the surface of the frame member 11 outside the groove 12, the strip 26 has a slight outward bend, as at 30, and at the exterior edge of the strip 26 there is a stamped rib 80 31, which is adapted to contact with the edge of the window sashes, providing a resilient seal and pressing the window sash against the opposed stop member. The weather strip 26 does not extend beyond the surface 32 of 85 the wooden strip 20, but terminates substantially at this surface in order to provide a weather strip of substantially the same size as the standard weather strip which has to be removed from the standard frame. 90

At one end of the strip 26 the flange 30 is continued and bent over at an angle somewhat less than a right angle to provide a resilient flange 33, extending substantially across the top of all that part of the wooden strip 20 which is exterior to the groove 12. It will be noted that the rectangular portion 21 of the wooden strip 20 is not covered by the flange 32 in the strip illustrated in Figure 2, but if desired the flange 32 may be extended backward to cover this portion 21, provided it is slit from the flange 30 for a distance extending from the corner 33 to the point 34, which is the edge of the groove, in order that the flange 30 may not be stiffened 105 by the flange 32, and in order to maintain the said flange 30 resilient when in assembled relation in the groove 12. The other end of the strip 26 may be likewise provided with a flange 33, or may terminate parallel to the bottom edge of the wooden strip 20, as shown in Figure 2. The wooden strip 20, as well as the rear flange 24 of the weather strip 26, is provided with a plurality of holes 35, which are adapted to receive screws or other 110 fastening members to hold the combined parting bead and weather strip in the groove 12. 115

The weather strip is secured to the wooden strip 20 by a plurality of nails driven 120 through the flange 24 at frequent intervals along its longest dimension, into the wooden strip 20. It will be observed that as illustrated in Figure 2, the resilient flange 33 has no stamped rib as at 31. In actual practice 125 the stamped rib 31 is conveniently made the full length of the weather strip 26, but in forming the flange 33, this rib may be flattened out, providing the finished form shown in Figure 2. 130

Referring to Figure 4, I have there illustrated a section of the upper sash showing the combined parting bead and weather strip 13 in the groove 12, with the flange 30 turned outwardly and bearing against the inside edge of the sash 14. It will be observed that the combined parting bead and weather strip 13 provide a resilient seal along the edge of the sash 14, and also press 10 the sash 14 against the exterior moulding strip 18. The combined bead and weather strip 13 extend from the top of the sash 14 to the bottom of the same sash, and a second combined bead and weather strip 36 extends 15 from the bottom of the sash 14, which is located at the top of the sash 15, to the bottom of the sash 15, but in order that the latter strip may provide a resilient seal with the lower sash, the strip is inverted in position, as shown in Figure 3, the side 39 of 20 the weather strip 36 pressing against the lower sash 15.

The weather strips 13 and 36 are then arranged with their ends abutting, so that 25 the flange 33 upon the one contacts with the flange 33 upon the other, effecting a sealing joint between the two weather strips and providing a complete weather seal along one side of both sashes. It will be obvious 30 that the weather strips 37 and 38 on the opposite side of the window may be arranged in a like manner, so that the sashes are provided with weather strips on each side consisting of a plurality of lengths which may 35 be inserted without removing the sash from the window frame.

It will thus be observed that I have invented a combined parting bead and weather strip which is capable of providing 40 a resilient seal along the total length of the windows, and which may be installed with a minimum of labor, without the removal of the sashes or their moulding strips.

While I have illustrated and described a 45 specific form of one embodiment of my invention, this is capable of many modifications without departing from the spirit of the invention, and I do not wish to be limited to the precise details of the construction set forth, but desire to avail myself of all advantages within the scope of the appended claims.

Having thus described my invention, what 50 I claim as new and desire to secure by Letters Patent of the United States is:

1. In combination with a window frame, a lower sash, and upper sash, one of said sashes being rabbeted in their juncture to permit passage of parting beads, external 55 and internal guide members for said sashes, a plurality of combined parting beads and weather strips of approximately the same length as said sashes whereby said beads and strips may be substituted for the standard

parting bead without removal of the sashes 60 from their guides.

2. In combination, a wooden parting bead of substantially T shaped cross section, a resilient weather strip having a flange attached along the top of said T, and a forwardly extending flange extending at right angles to said first flange and adapted to effect a seal against a window sash. 70

3. In combination, a wooden parting bead of substantially T shaped cross section, a 75 resilient weather strip having a flange attached along the top of said T, and a forwardly extending flange extending at right angles to said first flange and adapted to effect a seal against a window sash, said second named flange being provided with a stamped rib along its forward edge. 80

4. In combination, a wooden parting bead of substantially T shaped cross section, a resilient weather strip having a flange attached along the top of said T, and a forwardly extending flange extending at right angles to said first flange and adapted to effect a seal against a window sash, said second named flange having a portion extending 85 at right angles across the top of said bead to effect a resilient seal between separate beads. 90

5. In combination, a wooden parting bead of substantially T shaped cross section, a 95 resilient weather strip having a flange attached along the top of said T, and a forwardly extending flange extending at right angles to said first flange and adapted to effect a seal against a window sash, said second named flange being provided with a stamped rib along its forward edge, and having a portion extending across the end 100 of said bead to effect a seal between said end and the adjacent parts. 105

6. A parting bead consisting of a plurality of separate lengths of wood, and having a resilient weather strip attached thereto, and means to seal any juncture between said 110 lengths.

7. A parting bead consisting of a plurality of separate lengths of wood, said lengths having a resilient weather strip attached thereto, having means to seal the juncture between said lengths, and said 115 lengths being of similar construction but reversed in position to effect resilient seal with a plurality of sashes.

8. A parting bead for a window frame having a plurality of sashes, said bead consisting of a wooden bead and a resilient strip of metal attached thereto to effect sealing engagement with a sash, and said parting bead being approximately the length of 120 one of said sashes. 125

In witness whereof, I hereunto subscribe my name this 21st day of October, 1926.

WILLIAM F. KOELLING.

CERTIFICATE OF CORRECTION.

Patent No. 1,653,632.

Granted December 27, 1927, to

WILLIAM F. KOELLING.

It is hereby certified that error appears in the printed specification of the above numbered patent requiring correction as follows: Page 3, line 107, claim 6, strike out the word "and" and insert the words "each length"; and that the said Letters Patent should be read with this correction therein that the same may conform to the record of the case in the Patent Office.

Signed and sealed this 31st day of January, A. D. 1928.

Seal.

M. J. Moore,
Acting Commissioner of Patents.
